E. C. ANDERSON.
WARM AIR FURNACE.
APPLICATION FILED JULY 14, 1919.
1,323,809.

Patented Dec. 2, 1919.

INVENTOR
EDWIN C. ANDERSON,
by Bakewell & Church, M. S.

UNITED STATES PATENT OFFICE.

EDWIN C. ANDERSON, OF ST. LOUIS, MISSOURI, ASSIGNOR TO THE BUCK'S STOVE & RANGE COMPANY, OF ST. LOUIS, MISSOURI, A CORPORATION OF MISSOURI.

WARM-AIR FURNACE.

1,323,809.

Specification of Letters Patent. Patented Dec. 2, 1919.

Application filed July 14, 1919. Serial No. 810,734.

To all whom it may concern:

Be it known that I, EDWIN C. ANDERSON, a citizen of the United States, residing at St. Louis, Missouri, have invented a certain new and useful Improvement in Warm-Air Furnaces, of which the following is a full, clear, and exact description, such as will enable others skilled in the art to which it appertains to make and use the same.

10 This invention relates to warm air furnaces of the type in which the smoke pipe leading from the combustion chamber passes through a cold air chamber through which cold air or cool air circulates when the furnace is in operation.

15 The main object of my invention is to provide a warm air furnace of the general type referred to which is so constructed that the cool air or unheated air in the cold air chamber will not come in contact with the smoke pipe leading from the combustion chamber, thereby insuring a proper circulation of air in the cold air chamber, due to the fact that the temperature of the inflowing cold air is not increased by the heat which radiates from the smoke pipe.

20 Another object is to provide a warm air furnace of the general type referred to which is equipped with means for conserving and utilizing the heat that radiates from the portion of the smoke pipe that passes through the cold air chamber of the furnace through which the inflowing air circulates. Other objects and desirable features of my invention will be hereinafter pointed out.

25 Figure 1 of the drawings is a perspective view, partly broken away, of a portion of a warm air furnace constructed in accordance 40 with my invention.

Fig. 2 is a vertical sectional view of a portion of said furnace.

30 Fig. 3 is a horizontal sectional view, taken on approximately the line 3—3 of Fig. 2; and Fig. 4 is a vertical longitudinal sectional view of one side of the furnace.

35 Referring to the drawings which illustrate the preferred form of my invention, A designates the outer casing of my improved furnace and B designates an inner casing which is arranged inside of the casing A and spaced away therefrom so as to form a cold air chamber α down through which cold air circulates, as indicated by the

arrows in Fig. 2, when the furnace is in 55 operation, said cold air passing into the lower end of an air heating chamber γ and thence circulating upwardly through said heating chamber, as indicated by the arrows in Fig. 2. The smoke pipe C that 60 leads from the combustion chamber of the furnace projects laterally through the inner casing B and through the outer casing A, thereby causing a portion of said smoke pipe to be located in the space between the 65 inner and outer casings of the furnace. In the form of my invention herein illustrated the smoke pipe C is provided with a depending portion C' that constitutes a diving flue that lies in the space between the inner casing B and outer casing A, but it is immaterial whether or not the smoke pipe is 70 provided with a diving flue.

75 In order to prevent the cold air in the cold air chamber α from being heated by the heat which radiates from the smoke pipe, I have constructed the furnace in such a manner that the inflowing cold air is prevented from coming in contact with the portion of the smoke pipe that lies in the space between 80 the inner and outer casings of the furnace. Various means can be used for accomplishing this desirable result, but one convenient way of constructing the furnace is to incase the smoke pipe C and the depending portion 85 C' of same in a chamber ε formed by a housing arranged between the inner and outer casings of the furnace and provided with two vertical side walls 1, a top wall 2 and a bottom wall 3, as shown in Figs. 2 and 3. 90 The walls of said housing can be connected in any suitable manner to the outer casing A and inner casing B of the furnace, and the opening in the inner casing B, through which the smoke pipe and diving flue project is preferably made large enough so as 95 to form an unobstructed passageway between the air heating chamber γ and the chamber ε that surrounds the smoke pipe, thereby causing the heat that radiates from 100 the smoke pipe to be conserved and returned to the heating chamber γ where it is utilized.

105 A warm air furnace of the construction above described is more efficient than the furnaces of this general type heretofore in use, in that there is no liability of the heat which radiates from the smoke pipe coming in contact with the inflowing cold air in the

cold air chamber α , and thus raising the temperature of said air to such an extent that it does not circulate properly through the cold air chamber α . Such a furnace not only insures the air in the cold air chamber α being kept cool, but it also conserves and utilizes the heat which radiates from the portion of the smoke pipe that is located in the space between the inner and outer casings of the furnace. My invention is applicable to any type of warm air furnace in which the smoke pipe from the combustion chamber extends through the passageway through which cold air is admitted to the air heating chamber of the furnace; it is immaterial whether or not the smoke pipe is provided with a diving flue and the particular construction of the housing that incases the smoke pipe is immaterial, so long as it prevents the inflowing cold air from coming in contact with the smoke pipe and permits the heat that radiates from the smoke pipe to circulate back into the heating chamber of the furnace.

Having thus described my invention, what I claim as new and desire to secure by Letters Patent, is:

1. A warm air furnace provided with a passageway through which cold air is admitted to the air heating chamber of the furnace, a smoke pipe having a portion arranged in said passageway, and means for preventing the inflowing cold air in said passageway from coming in contact with said smoke pipe.

2. A warm air furnace provided with a passageway through which cold air is admitted to the air heating chamber of the furnace, a smoke pipe having a portion arranged in said passageway, means for preventing the inflowing cold air in said passageway from coming in contact with said smoke pipe, and means for conserving and utilizing the heat that radiates from the portion of the smoke pipe arranged in said passageway.

3. A warm air furnace, comprising an inner casing and an outer casing spaced apart so as to form a cold air chamber, a smoke pipe leading from the combustion chamber of the furnace and projecting laterally through said casings, and means for preventing the cold air in said cold air chamber

from coming in contact with said smoke pipe.

55

4. A warm air furnace, comprising an inner casing and an outer casing spaced apart so as to form a cold air chamber, a smoke pipe leading from the combustion chamber of the furnace and projecting laterally through said casings, means for preventing the cold air in said cold air chamber from coming in contact with said smoke pipe, and means for conserving and utilizing the heat that radiates from the portion of the smoke pipe arranged in the space between the inner and outer casing of the furnace.

5. A warm air furnace, comprising an air heating chamber, a cold air chamber surrounding said air heating chamber, a smoke pipe leading from the combustion chamber of the furnace and provided with a portion arranged in said cold air chamber, and a housing in said cold air chamber that incases said smoke pipe and prevents the inflowing cold air from coming in contact with same.

6. A warm air furnace, comprising an air heating chamber, a cold air chamber surrounding said air heating chamber, a smoke pipe leading from the combustion chamber of the furnace and provided with a portion arranged in said cold air chamber, a housing in said cold air chamber that incases said smoke pipe and prevents the inflowing cold air from coming in contact with same, and a passageway from the interior of said housing to said air heating chamber.

7. A warm air furnace, comprising an outer casing, an inner casing arranged inside of said outer casing and spaced away therefrom so as to form a cold air chamber down through which cold air circulates into the lower end of the air heating chamber formed by said inner casing, a smoke pipe projecting laterally through said inner and outer casing and provided with a diving flue located principally in said cold air chamber, and a housing arranged between the inner and outer casings of the furnace for preventing the inflowing cold air from coming in contact with said smoke pipe and diving flue, the inner casing of the furnace being so constructed that the interior of said housing is in direct communication with the air heating chamber of the furnace.

EDWIN C. ANDERSON.
